UNITED STATES PATENT OFFICE

DAVID C. KLAUSMEYER, OF CINCINNATI, OHIO, ASSIGNOR TO THE CINCINNATI BICK-FORD TOOL COMPANY, OF OAKLEY, CINCINNATI, OHIO, A CORPORATION OF OHIO

EQUALIZED ARM CLAMP

Application filed March 10, 1925. Serial No. 14,542.

This invention relates to radial drills and it deals more particularly with means for effecting translation of the radial arm on the column and for securely clamping the arm to the column in any desired position of adjustment.

Radial drills as commonly constructed, comprise an upright column, a laterally projecting arm slidably mounted on the column and a drill-head adjustably supported on the arm. For purposes well understood, the arm must admit of vertical adjustment on the column and, before the drilling operation is begun, the arm must be securely clamped to the column. The translation of the arm is usually effected by means of a power driven screw having a threaded engagement with a fixed nut carried by the arm, and means is provided to determine the direction of rotation of the screw to cause it to raise or lower the arm and to discontinue the rotation when no translation is required. The arm is frequently formed with a girdle encircling the column, and to provide for the securing of the arm to the column the girdle is split vertically and one or more bolts are provided to contract the split girdle to cause it to grip the column.

In certain prior constructions the girdle has been split its entire length while in other constructions it has been split only at its opposite ends, the intermediate portion remaining solid. In both of these prior constructions the clamping means have been arranged in vertical alignment and at the same side of the column. Also in both forms of construction the actuating means for the clamps have been entirely separate and distinct from the controlling means for the arm translating means.

This invention has for an object to provide improved means for clamping the arm to the column whereby the arm may be more tightly clamped than has heretofore been possible and in which the clamping may be effected with substantially less effort on the part of the operator.

Another object of the invention is to provide an improved arm translating mechanism adaptable both to radial drills in which

power is brought into the machine tool at the base of the column, flows through a vertical shaft in the column, and finally to the arm shaft, and also to that type of radial drill in which the driving motor is supported on a rearward extension of the arm.

A further object of the invention is so to co-ordinate the arm clamping mechanism and the arm translating mechanism that a single lever may be utilized to control both mechanisms, and to provide means to prevent both of said mechanisms from being active at the same time.

Another object of this invention is to provide an arm translating mechanism and an arm clamping mechanism both adapted to be actuated by a single hand lever and to provide automatically acting means to throw said arm translating means into a neutral position before the arm clamping may be actuated.

It will readily be perceived, inasmuch as the arm extends laterally from the arm and carries the drill head, that due, both to the weight of the parts and the leverage caused by the location of the drill-head adjacent the outer end of the arm, a great bending strain will be transmitted to the column. This strain is, of course, resisted by the column which results in the tendency of the arm to pivot about a horizontal axis intermediate the ends of the girdle. This strain causes the upper end of the girdle at the side opposite to that to which the arm extends, to be pulled laterally against the column and to produce a certain amount of slack at the upper end of the girdle of the arm side of the column. Likewise the lower end of the girdle is moved laterally in the opposite direction which causes it to bear against the column beneath the arm and to produce slack at the lower end of the girdle at the side opposite to that to which the arm extends.

This invention therefore has for an object to provide separate and independent clamps located at the opposite ends of the girdle and acting where the lateral pressure is the least, that is upon the slack sides of the girdle, to contract the girdle and cause it to firmly clamp the column.

A further object of the invention is to provide a single actuating means for both of the clamps and to provide an equalizing device between the two to insure complete actuation of both clamps.

Still another object of this invention is so to form the arm and the girdle as to provide a reinforcing element integral with the arm and extending around the girdle and merging thereinto at the side opposite to that to which the arm projects, thereby to transmit to the opposite side of the girdle the lateral pull produced by the weight of the arm and drill head.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Fig. 1 is an elevation, partly in section, of a radial drill embodying the present invention. Fig. 2 is a plan of the parts carried at the upper end of the column for rotating the arm elevating screw in reverse directions. Fig. 2^a is a diagrammatic view illustrating the means for automatically rendering ineffective the arm translating mechanism. Fig. 3 is a detail plan of the rear end of the radial arm and girdle, showing more particularly the means to clamp the girdle to the column. Fig. 4 is a diagrammatic view showing various positions of the combined clamp-actuating and arm translating controlling lever. Fig. 5 is a view similar to Fig. 1 but showing the invention embodied in a radial drill having arm translating mechanism carried by the radial arm, said translating mechanism being shown in development adjacent the column. Figs. 6 and 7 are views similar to Figs. 2 and 3 but of the drill shown in Fig. 5. Fig. 8 is a detail section on the line 8-8 of Fig. 5. Fig. 9 is a detail section of the lower portion of the arm clamping and arm translating controlling device shown in Fig. 5.

Referring more particularly to the drawings and especially to Figs. 1, 2, 3 and 4 the invention is disclosed as embodied in a radial drill including an upright column 1 upon which is slidably mounted a girdle 2 formed integral with a radial arm 3. The column shown is of the cylindrical type and the girdle completely embraces the column but it is to be understood that this invention is also adaptable to various other types of columns and contemplates various other means for slidably mounting the arm on the column

and for securing the arm to the column in its various positions of adjustment. Also the column 1 may be a stationary member or, to permit of horizontal movement of the arm, it may be in the nature of a sleeve rotatably supported upon a central post. The radial arm carries the usual drill-head within which the usual drill spindle is rotatably journaled. Inasmuch as the construction of the drill head and the rotating means for the spindle are old and well known and as they form no part of the present invention, illustration and detail description thereof is deemed unnecessary.

Translation of the arm on the column may be effected by means of a screw 4 rotatably journaled in bearings 5 and 6 provided at the upper and lower ends, respectively, of the column 1 and having a threaded connection with the arm 3. Power to rotate the screw may enter the column at any suitable place and flow through a shaft 7 journaled coaxial with the column. A cap 8 is secured upon the upper end of the column and above this cap is secured to the shaft 7 a relatively wide gear 9 constituting one driver for a tumbler gear 10 later to be referred to. A gear 11, fixed to a shaft 12, parallel with the shaft 7, meshes with the gear 9 and serves as a driver for a gear 13 carried by a vertical shaft 14. The gear 11 is approximately one-half the width of the gear 9 and the gear 9 projects above the gear 11 for a purpose later to be explained. The shaft 14 acts, through any suitable train of mechanism, to rotate the drill spindle, not shown. Fixed to the shaft 12 above the gear 11 is a gear 15 which constitutes a second driver for the tumbler gear 10. The tumbler gear is journaled upon a pin 16 carried by one arm 17^a of a bell-crank lever 17, fulcrumed upon the upper end of the elevating screw 4. A gear 18 is secured upon the screw 4 beneath the lever 17 and is maintained permanently in mesh with the tumbler gear. It will readily be perceived that inasmuch as the gears 9 and 15 are rotated in reverse directions, and as the tumbler gear is adapted to connect either of these gears with the gear 18, the direction of rotation produced in the elevating screw will depend upon with which of the driving gears the tumbler gear is engaged. The other arm 17^b of the bell-crank lever is provided with a gear-segment 19 maintained permanently in mesh with a similar segment 20 secured upon the upper end of a rock-shaft 21 journaled lengthwise of the column 1.

Fixed upon the lower end of the shaft 21 is a collar 24 having an annular flange 25 provided with a notch 26. The collar is also formed with a portion 27 in the nature of a bushing by means of which the rock-shaft is journaled in a boss 28 integral with the column 1. The upper end of the rock-

shaft 21 is journaled in a bearing 29 in the cap 8. The rock shaft 21 is adapted to be oscillated by a combined clamp-actuating and arm-translating controlling lever 30 fixed upon a tube 31 loosely journaled coaxial with the rock shaft in bearing bosses 2^a and 2^b provided by the girdle 2. A spring-plunger 32, carried by the lever, is adapted to enter the notch 26 and, when in said notch, affords a driving connection between the lever and the collar 24 carried by the rock-shaft, whereby the shaft 21 will be caused to turn with the lever whenever the latter is moved by the operator. To limit the movement of the lever 30 when connected with the rock-shaft, the hub of the gear-segment 20 is provided with abutments 33 and 34 adapted to engage stop screws 35 and 36 adjustably carried by the cap 8. A trigger 37, carried by the lever 30 and connected with the plunger 32, serves to move the plunger lengthwise against the action of a spring 38 to withdraw the end of the plunger from the notch 26 to permit the lever 30 to be disconnected from the rock-shaft when the desired translation of the arm has been effected. The lever 30 having been disconnected from the translating mechanism it may then be given a further movement after the abutment has engaged the stop screw, to actuate the clamps. Upon release of the lever from the translating mechanism the tumbler gear lever 17, segment 20, shaft 21 and collar 24 are automatically shifted to a neutral position as will now be described. Referring now to Fig. 2^a it will be seen that, due to the direction of rotation of the gears 9 and 15 and to the angle of pressure of the teeth of the driving gears 9 and 15 on the tumbler gear, the pressure of the driving gears will (unless prevented by manually holding the lever 30 in one of its arm translating positions) throw the tumbler gear out of mesh with the driving gear and thereby discontinue the rotation of the arm translating screw. A spring detent 22, carried by the cap 8, is adapted to engage a notch 23 formed in the hub of the segment 20 to arrest the movement of the lever 17 when the tumbler gear is forcibly disconnected from either of the driving gears to hold the tumbler gear in its neutral position between the gears 9 and 15.

The arm having been translated to the desired position, it must be firmly locked to the column before the drilling operation is begun. This invention provides a highly efficient and easily manipulated clamping mechanism for effecting this result. Referring now more particularly to Fig. 3 it will be seen that the rear wall 3^a of the arm is located at one side of the girdle 2 and is formed with a wide extension or strengthening rib 3^b extending a substantial dis-

tance around the girdle and merging thereinto at 3^c at the side of the girdle opposite to that from which the arm projects. This rib 3^b greatly strengthens the upper end of the girdle at the side opposite to that from which the arm projects and at the point where the weight of the arm and drill-head exert a heavy lateral pressure on the column. It will readily be perceived that inasmuch as the arm projects laterally from the girdle and supports the drill-head, the combined weight of the arm and drill-head will exert a strain upon the column tending to overturn it. This strain is resisted by the column with the result that the strain tends to cause the arm to pivot about a horizontal axis intermediate the ends of the girdle thereby causing the opposite ends of the girdle to transmit to the column lateral pressures, in opposite directions, as represented by the arrows *a* and *b* in Fig. 1. These lateral pressures at *a* and *b* cause the opposite sides of the girdle to be moved away from the column at the opposite sides and produce slack at the points *c* and *d*; the slack being shown as exaggerated at the point *c* in Fig. 3.

This invention proposes an arrangement of clamps which with less effort on the part of the operator, more securely locks the girdle to the arm than has heretofore been possible. To that end the girdle is split at its opposite ends as at *e* and *f* on the sides where the slack is produced. These splits produce opposed clamping portions *g*—*h* and *i*—*j* through which extend bolts 39 and 40 respectively. Pins 41 and 42 fixed in the bolts extend outwardly therefrom and enter grooves 43 and 44 to prevent rotation of the bolts. Nuts 45 and 46, threaded upon one end of the bolts, bear against walls 3^a and 3^b of the arm 3 and prevent endwise movement of the bolts in one direction. Upon the opposite ends of the bolts 39 and 40 are threaded clamp-nuts 47 and 48 provided with laterally extending offset actuating arms 47^a and 48^a terminating in gear-segments 47^b and 48^b respectively. To the tube 31 is splined, intermediate the bearing bosses 2^a and 2^b, a sleeve 49 having formed integral therewith, at its opposite ends, worms 50 and 51 permanently in mesh with the gear segments 47^b and 48^b respectively. Thus it will be perceived that rotation of the tube 31, by the lever 30, will through the sleeve 49, worms 50 and 51 and gear-segments 47^b and 48^b, cause the nuts 47 and 48 to be turned on the bolts 39 and 40 to either contract or expand the portions *g*—*h* and *i*—*j* of the girdle, dependent upon the direction of rotation of the sleeve. From the foregoing it will be seen that the manually actuable lever 30 affords means for controlling both the arm translating mechanism and the arm clamping mechanism.

Referring now to Fig. 4 it will be seen that although the lever 30 controls both, the arm translating mechanism and the arm clamping mechanism, these mechanisms are so designed and co-ordinated that they both 5 may not be effective at the same time; thus the danger of clamping the arm during its translation or vice versa is precluded. In the position designated as *v* the arm translating mechanism is in neutral and the arm is clamped to the column. Now if it is desired to change the elevation of the arm the lever 30 is first moved to the position *w* which movement turns the tube 31 and, through the mechanism above described, causes the clamps to be released to free the arm from the column. The next movement 10 of the lever is to the position *x* where the spring plunger 32 engages the notch 26 in the collar 24 fixed to the arm translation controlling shaft 21. (It is to be remembered that upon the previous actuation of the clamps the translating mechanism, including the collar 24, was automatically returned to its neutral position.) This movement 15 of the lever from the position *v* to the position *x* opens the clamps further but this is merely an idle movement since the clamps have already released the column. From 20 the position *x* the lever may be moved either to the position *y* or to the position *z*. If moved to *y* the gear segment 20 will move the lever 17 clockwise, as viewed in Fig. 2, and cause the tumbler gear to be meshed 25 with the gear 15, whereupon the screw 4 will be rotated in a direction to elevate the arm, and the abutment 34 will be brought into engagement with the stop-screw 36 thus preventing further movement of the lever to 30 the right while the plunger engages the notch 26. Movement of the lever from the position *x* to the position *z* moves the lever 35 17 anti-clockwise and meshes the tumbler gear with the driving gear 9 thereby rotating the screw in the reverse direction and causing the arm to be lowered. The desired 40 adjustment of the arm having been made, the operator presses the trigger 37 which releases the plunger from the notch 26 and 45 permits the tumbler gear automatically to be moved to its neutral position thereby bringing the arm translating mechanism to rest. The lever 30 may then be moved to its 50 position *v* thereby clamping the girdle to the column in its new position.

It will readily be perceived that inasmuch as a single actuator is provided for both clamps, one clamp might be tightly closed before the other and, unless special 55 provision was made, the movement of the actuating lever would thereby be arrested and the looser clamp could not be caused to function. This invention overcomes this difficulty by a very ingenious equalizing device. Upon actuation of the lever to close

the clamps should one clamp be closed before the other, a further rotary movement of the lever 30 and sleeve 49 will cause the sleeve to be both rotated and translated on the tube 31 to which it is splined, thereby 70 permitting the looser clamp also to be closed and the pressure exerted by the two clamps will be equalized.

The worm and gear connection between the actuating lever 30 and the clamps constitutes a power multiplying device and therefore, with this device, the clamps may be more tightly closed with a predetermined pressure on the lever than if the lever was connected directly to the nuts 47 and 48. 75

To prevent the arm being elevated or depressed an undue amount, automatic limit stops are provided. These consist of cams 52 and 53 carried respectively by a collar 54 fixed to the shaft 21 adjacent the cap 8, and by the hub 30^a of the lever 30, whereupon extreme translation of the arm, they are engaged by studs 55 and 56 carried by the girdle 2. This engagement causes the shaft 21 and tube 31 to be turned thereby 80 automatically rendering the translating mechanism ineffective.

Figs. 5, 6, 7, 8 and 9 show this invention embodied in a radial drill equipped with a different form of arm translating mechanism. As shown in these figures the column, the girdle and the clamping mechanism are substantially the same as described in reference to Figs. 1, 2 and 3 and reference may therefore be had to the above description 95 for the construction and operation of the clamping mechanism. For convenience the same reference characters have been applied to Figs. 6, 7, 8 and 9 as were used in connection with Figs. 1, 2 and 3 in so far as the 100 parts are alike.

The arm translating mechanism disclosed more particularly in Figs. 5, 6 and 7 comprises a power driven shaft 7 which may be rotated by any suitable mechanism. This 105 shaft is preferably located coaxial with the column 1 and carries at its upper end, above the cap 8, a gear 60 which, (through an idler gear 61 journaled on a stud 62 carried by the cap) drives a similar gear 63 fixed upon an upright shaft 64. Non-rotatably carried by the column 1 is a screw 65 upon which is threaded a nut 66 provided with a shoulder 67 supporting an anti-friction thrust bearing 68 upon which the weight of the arm is 110 supported. A normally inactive auxiliary safety nut 69 also is threaded upon the screw 65 and serves to support the arm upon failure of the nut 66, as by the stripping 115 of the threads. Within the arm 3 is rotatably journaled the hub 70^a of a miter gear 70 having a splined connection with the shaft 64. Thus the gear may move vertically with the arm while maintaining a driving connection with the shaft. Fixed 120

to the hub 70^a as by means of a screw 71 is a friction clutch cup 72 within which is coaxially arranged one end 73^a of a clutch sleeve 73 rotatably journaled in a bearing 74 supported by the arm 3. An expandible clutch ring 75 located between the inner face of the cup 72 and the outer face of the end 73^a serves at certain times to lock the two together for purposes later to be described. 5 Rotatably and translatable mounted on the shaft 64, within the sleeve 73, is a second sleeve 76 having formed integral with it, at its lower end a gear 77. The sleeve 76 is non-rotative relative to the sleeve 73. The 10 friction clutch 72, 73, 75 is of the type disclosed in United States patent to Schauer No. 756,185 dated March 29, 1904, and the ring 75 is adapted to be expanded by means of a lever 78 carrying a contact-screw 79. 15 The inner end of the screw tracks a groove 80 milled lengthwise in the sleeve 76. This groove terminates at its opposite ends in cam surfaces 81 and 82 which upon sufficient translation of the sleeve 76 forces the screw 79 outwardly thereby rocking the lever 20 78 and expanding the clutch ring 75 to establish a driving connection between the members 72 and 73. Inasmuch as the friction-clutch is substantially the same as that disclosed in the above noted Schauer patent, further description thereof is deemed unnecessary. A spring detent 83 carried by the member 73 is adapted to engage any one of three detent notches n , n' and n'' to hold 25 the sleeve 76 in any one of its three vertical positions.

Fixed to the nut 66 is a gear-unit 84 providing gears 85 and 86. An idler gear 87 is rotatably journaled on a stud 88 fixed in 30 the arm 2 and is maintained permanently in mesh with the gear 85. As shown in Fig. 5 the gear 77 is in its neutral position and no power is being transmitted from the shaft 64 to the nut 66. Means is provided for 35 shifting the gear 77 either downwardly from its neutral position into engagement with the gear 86, whereby power is transmitted to the nut 66 in one direction, or upwardly into engagement with the idler gear 87 40 whereby power is transmitted to the nut 66 in the opposite direction. Fig. 7 illustrates in plan the relative positions of the gears 77, 86 and 87 whereby the gear 77 45 selectively may be caused to mesh with either of the other two. The ends of the teeth of the gears 77, 86 and 87 are preferably tapered to facilitate meshing.

Shifting of the gear 77 is effected manually by the combined clamp-closing and arm-translating controlling lever 30. As shown in Fig. 5 the plunger 32, carried by the lever 30, is formed with a lateral projection or head 32^a which tracks the outer periphery of a bearing boss 89, provided, at one point, 50 with a notch 90 and a clearance groove 91.

The shaft 21 has secured to its lower end a collar 92 provided with a notch 93, which, in the neutral position of the arm translating mechanism is adjacent and in line with the notch 90. Thus when the lever 30 is turned to a predetermined point (thereby releasing the clamps) the projection 32^a passes through the notch 90 and engages the walls of the notch 93 thereby operatively connecting the lever 30 with the shaft 21. 55 Upon the upper end of shaft 21 is secured a gear segment 94 which meshes with a similar segment 95 fixed to the upper end of a shaft 96 parallel with the shaft 64. Rotatably journaled in the arm 3 is a miter gear 80 97 having a splined connection with the shaft 96. A similar miter gear 98 is fixed upon a shaft 99 also journaled in the arm and is maintained permanently in mesh with the gear 97. An arm 100 secured upon the opposite end of the shaft 99 carries a yoke 101 which tracks an annular groove 76^a in the sleeve 76. From the foregoing it will be perceived that rotation of the shaft 21 in a clockwise direction, as viewed in plan will, 85 through the elements 94, 95, 96, 97, 98, 99, 100 and 101, shift the gear upwardly into engagement with the idler gear 87 and the nut 66 will be rotated in a direction to elevate the arm. Likewise rotation of the 90 shaft 21 anti-clockwise will shift the gear 87 downwardly into mesh with the gear 86 and the nut 66 will be rotated in the opposite direction to lower the arm. The initial axial movement of the gear 77 and its sleeve 100 95 76 causes the gear to be partly meshed with either the gear 86 or the idler 87 dependent upon the direction of translation. A continued movement causes either the cam-surface 81 or the cam-surface 82 to contact with the screw 79 carried by the clutch-actuating lever with the result that by the time the gears have been completely meshed the friction clutch has been actuated to lock together the clutch cup 72 and the sleeve 73 110 whereby rotation is transmitted to the gear 77 and finally to the nut 66.

Journaled lengthwise of the arm 3 is the usual arm-shaft 102 from which power is taken to rotate and translate the drill-spindle. The shaft 102 receives power through a miter-gear 103 fixed to the shaft and meshing with the miter-gear 70 secured upon the constantly driven shaft 64. 115

Referring now to Fig. 7 it will be seen 120 that the principle of operation of the arm translating and arm clamping mechanisms shown therein is very similar to that above described in connection with Fig. 4. The combined arm clamping and arm translating 125 controlling lever 30 is adapted to occupy any one of the positions p , r , s , t , or u . In the position p the translating mechanism is entirely disconnected from the lever 30 and is inactive and the arm is clamped to 130

the column. Movement of the lever to the position *r* releases the clamps to permit subsequent translation of the arm. The lever is then moved to the position *s*, in which position the plunger head 32^a passes through the notch 90 and engages the notch 93 in the collar 92 secured upon the shaft 21. The clamps being now released and the lever connected with the translating mechanism, the lever may be moved either clockwise to the position *u* to lower the arm, or anti-clockwise to the position *t* to elevate the arm as previously described. Abutments 33 and 34 engage the stop screws 35 and 36 and limit the movement of the lever 30 when connected with the translating mechanism. The lever may again be moved to close the clamps only by first bringing it to the position *s* (which places the translating mechanism in neutral) and then withdrawing the plunger head 32^a from the notches 93 and 90. Thus it will be perceived that although the lever 30 controls both the arm translating and the arm clamping mechanism, the simultaneous actuation of these mechanisms is effectively precluded.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A drilling machine combining a column; a projecting arm supported on and adjustable on said column; and means for clamping said arm on said column, said clamping means being located to be effective only at the upper part of the arm on the projecting side of the column, and at the lower part of the arm on the opposite side whereby the arm may be clamped relatively easy and without disturbing the adjusted position.

2. A drilling machine combining a column; a girdle vertically movable on the column; a plurality of clamps at the opposite sides of the girdle and column respectively to secure the girdle to the column; and a single actuating means for all of said clamps.

3. A drilling machine combining a column; an arm projecting laterally from the column and provided with a girdle embrac-

ing the column, said girdle being split at its opposite ends and at its opposite sides; and means to contract said split portions to lock the girdle to the column.

4. A drilling machine combining a column; an arm projecting laterally from said column and vertically movable thereon; and means located at the opposite sides of said column, and adjacent the upper and lower sides respectively of the portion of the arm movable thereon to secure said arm against vertical movement on said column.

5. A drilling machine combining a column; an arm projecting laterally from said column and having a girdle slidable thereon; means, located at the side of the column to which the arm projects, to clamp the upper portion of said girdle to said column; and means located at the opposite side of the column to clamp the lower portion of said girdle to the column.

6. A drilling machine combining a column; an arm projecting laterally from said column and having a girdle slidable thereon; means, located at the side of the column to which the arm projects, to clamp the upper portion of said girdle to said column; means located at the opposite side of the column to clamp the lower portion of said girdle to the column; and a single actuating means for said clamps.

7. A drilling machine combining a column; an arm projecting laterally from said column and having a girdle slidable thereon; means, located at the side of the column to which the arm projects, to clamp the upper portion of said girdle to said column; means located at the opposite side of the column to clamp the lower portion of said girdle to the column; an actuating lever associated with each clamp; and a single controlling mechanism for said levers, said controlling mechanism embodying an equalizing device.

8. A drilling machine, combining a column; an arm vertically movable on said column; a plurality of independent clamps located at diametrically opposite sides of said column at the upper and lower sides respectively of said arm to secure said arm to said column; and a single actuating mechanism for all of said clamps, said actuating mechanism including an equalizing device.

9. A drilling machine combining a column; an arm extending to one side of the column and vertically movable thereon; two independent clamps carried by said arm and acting respectively upon the sides of said column adjacent to and remote from the arm for securing said arm to said column, said clamps each including relatively movable portions adapted to grip said column; a bolt and a nut for drawing said portions together; a clamp-actuating arm carried by one of said last named elements; a single

member having an operative connection with both of said clamp-actuating arms; and means to move said member to cause it to oscillate said arms thereby to actuate said clamps, said member and arm being so connected as to provide means for equalizing the pressure of said clamps.

10. A drilling machine combining a column; an arm vertically movable on said column; two independent clamps for securing said arm to said column, said clamps each including a nut and a draw-bolt; an arm carried by one of said last named elements; a rotatable and translatable member having a threaded connection with said arms; means to rotate said member to cause it to oscillate said arms thereby to actuate said clamps; and means permitting said member to move axially to equalize the pressure exerted by said clamps.

11. In a radial drill; an upright column; a girdle vertically movable on said column; an arm integral with said girdle and extending horizontally therefrom, said arm being located mainly at one side of a vertical plane parallel to said arm and intersecting the axis of said column, said arm and girdle being so constructed that the rear wall of the arm extends around the girdle approximately 180° and forms a reinforcement for said girdle at the side opposite to that to which the arm extends to take a portion of the lateral thrust imposed on said girdle by the weight of said arm; clamping means acting upon the upper end of said girdle adjacent the arm side thereof, another clamping means acting upon the lower end of said girdle opposite to said arm side.

12. In a radial drill, an upright column; a girdle vertically movable on said column, said girdle being split at its opposite ends and at diametrically opposite sides; an arm formed integral with said girdle and extending horizontally to one side thereof; a rib integrally connecting said arm with said girdle at the side opposite to that to which the arm extends to transmit to the opposite side of the girdle a portion of the lateral strain caused by the weight of the arm; and means acting upon the upper and lower ends of said girdle at the sides adjacent to and remote from the arm, respectively, clamp said girdle to said column.

13. A drilling machine combining a column; an arm vertically movable on said column; means to translate said arm on said column; means to clamp said sleeve to said column; a single actuating element for said translating means and said clamping means; and means selectively to couple said actuating element with the translating and clamping means.

14. A drilling machine combining a column; an arm vertically movable on said column; means to clamp said arm to said

column; a lever permanently connected to actuate said clamping means; means to translate said arm on said column; shiftable means for rendering said translating means operative; means for selectively connecting or disconnecting said lever to said shiftable means; and means to prevent the simultaneous actuation of the translating and clamping means.

15. A drilling machine combining a column; an arm translatable mounted on said column; means to translate said arm on said column; means to clamp said arm to said column; a single controlling lever permanently connected with one of said means and normally wholly disconnected from the other of said means but adapted at will to be connected with the other of said means; and means to control the action of said lever to insure the inoperativeness of said permanently connected means before the other means is rendered effective.

16. A drilling machine combining a column; an arm translatable mounted on said column; mechanism to translate said arm on said column; means to control said translating mechanism, said controlling means including an oscillatory shaft operatively connected with said translating means; means to clamp said arm to said column; actuating means for said clamp including a clamp actuating arm; a sleeve rotatably journaled co-axial with said shaft and having an operative connection with said arm; a clamp actuating lever permanently connected with said sleeve; means active in the clamp releasing position of said lever to permit said lever to be secured to said shaft; and means to limit the movement of said lever when connected to said shaft to prevent actuation of said clamp.

17. A drilling machine combining a column; an arm slidably mounted on the column; means to translate the arm on the column, said means including a screw having a threaded connection with said arm; means to rotate said screw in reverse direction, said last named means including a gear on said screw; a tumbler gear permanently in mesh with said gear; two oppositely rotated driving gears with which said tumbler gear is adapted selectively to be meshed, the axis of said screw, driving gears and tumbler gear being so located with respect to each other and to the direction of rotation of said driving gears that the pressure of said driving gears on the tumbler gear tends to disengage the tumbler gear from the driving gears; and a spring detent to yieldingly hold the tumbler gear in its natural position.

18. A drilling machine combining a column; an arm slidably mounted on said column; means to translate said arm on said column; means to clamp said arm to said column; a single control lever for said arm.

translating and arm clamping means, said lever being movable a predetermined extent to render effective said translating means; means to limit the movement of said lever when connected with said translating means; means to disconnect said lever from the translating means; means acting at the disconnection of the lever from the translating means to render the translating means ineffective, said lever then being adapted to actuate said clamping means.

19. In a drilling machine, a column; an arm slidably mounted on the column; means to translate the arm on the column, said means including a screw having a threaded connection with said arm; a gear on said screw; a lever fulcrumed co-axial with said screw; a tumbler gear carried by said lever and maintained permanently in mesh with said first named gear; two oppositely rotated driving gears with which said tumbler gear is adapted selectively to be meshed; a shaft; an operative connection between said shaft and said lever; means to oscillate said shaft to cause it to shift said lever and said tumbler gear, said last-named means including an actuating lever releasably attached to said shaft; means to release said actuating lever from said shaft, said driving gears and tumbler gear being so related that the tumbler gear is automatically disengaged from the driving gear when the actuating lever is released; and means to retain said tumbler gear in its neutral position.

20. A drilling machine combining a column; an arm slidably mounted on the column; means to translate the arm on the column; means to clamp the arm to the column; a single controlling lever for said arm translating means and said arm clamping means, said controlling lever being permanently connected with said clamping means; a rock shaft adapted to control the translating means; a spring plunger carried by said lever and adapted, in the clamp releasing position of said lever, to engage said rock shaft; and a guard to limit the movement of said lever when connected to said shaft and to insure the inaction of said translating means before said clamping means is rendered effective.

21. In a drilling machine, a column; an arm slidably mounted on the column; means to translate the arm on the column, said means comprising a screw supported from the column; a nut rotatably and non-translatably journaled in the arm and threaded upon said screw; two gears carried by said nut; an idler gear in mesh with one of said gears; a power driven shaft parallel with said screw; a gear loosely journaled on said shaft; means selectively to shift said last named gear into mesh with one of the gears on the nut or into mesh with said idler gear; and means active after said gears have been

meshed to secure said loosely journaled gear to said shaft to cause rotation of said nut and thereby vertical movement of the arm.

22. In a drilling machine, a column, an arm slidably mounted on the column; means to translate the arm on the column, said means comprising a screw supported by said column; a nut rotatably and non-translatably carried by the arm and threaded upon said screw; a gear on said nut; an arm shaft; a shaft parallel with said screw; miter gears secured to said last mentioned shaft and said arm shaft and serving to rotate one of said shafts from the other; a gear loosely journaled on the shaft parallel with the screw; means to shift said last named gear into mesh with the gear on said nut; and means to lock said loosely journaled gear to one of said miter-gears to effect rotation of said nut and thereby translation of the arm.

23. A drilling machine as set forth in claim 21, characterized by this that the means to shift the loosely journaled gear comprises an oscillatory shaft; a miter gear secured to said shaft; a second miter gear in mesh with the first named miter gear; a gear shifting arm engaging said loosely mounted gear and adapted to be oscillated by said second miter gear; and a lever to turn said oscillatory shaft.

24. In a drilling machine, a column; an arm slidably mounted on the column; means to translate the arm on the column, said means comprising a screw carried by the column; a nut rotatably and non-translatably carried by the arm and threaded upon said screw; a gear secured to said nut; a power driven gear normally disconnected from the gear on said nut; means to clamp said arm to said sleeve; and a single lever to actuate said arm clamp and to cause said power driven gear to be shifted into mesh with the gear on said nut.

25. A drilling machine as set forth in claim 24 characterized by this that the single actuating lever for the arm translating mechanism and the arm clamping mechanism is so controlled as to permit the actuation of the clamp only when the translating mechanism is inoperative and actuation of the translating mechanism only when the clamp is released.

In witness whereof, I have hereunto subscribed my name.

DAVID C. KLAUSMEYER.

CERTIFICATE OF CORRECTION.

Patent No. 1,764,514.

Granted June 17, 1930, to

DAVID C. KLAUSMEYER.

It is hereby certified that error appears in the printed specification of the above numbered patent requiring correction as follows: Page 7, line 53, claim 12, before the word "clamp" insert the word to; same page, line 125, claim 17, for "natural" read neutral; and that the said Letters Patent should be read with these corrections therein that the same may conform to the record of the case in the Patent Office.

Signed and sealed this 2nd day of September, A. D. 1930.

M. J. Moore,
Acting Commissioner of Patents.
